UNITED STATES PATENT OFFICE.

JACOB C. N. WISTENDAHL, OF BROOKLYN, NEW YORK.

ROPE-LOCK.

1,164,692.

Specification of Letters Patent.

Patented Dec. 21, 1915.

Application filed April 7, 1915. Serial No. 19,633.

To all whom it may concern:

Be it known that I, JACOB C. N. WISTENDAHL, a citizen of the United States of America, and a resident of Brooklyn, Kings county, New York, have invented certain new and useful Improvements in Rope-Locks, of which the following is a specification.

This invention relates to improvements in 10 rope locks and similar devices.

The object of the invention is to provide a rope lock or rope clamp of generally improved construction.

One object of the invention is to provide 15 a rope lock constructed entirely of metal wire or similar material which may be bent easily into the desired shape.

Another object is to provide an efficient 20 rope clamp adapted to be manufactured at a low cost.

Still another object of the invention is to provide a rope lock of relatively flat design so that it may be conveniently carried about.

Other objects will appear as this specification 25 proceeds, while reference is had to the accompanying drawings showing the preferred form of my invention and in which—

Figure 1 is a plan view of a rope lock embodying my invention. Fig. 2 is an edge 30 view, the rope being removed at the one end of the lock. Fig. 3 is an edge view illustrating the use of the rope lock when the rope is to be slackened with parts broken away, and Fig. 4 shows a modification.

35 Rope locks for locking a rope in a given adjusted position are used mostly in connection with clothes lines, on boats, for tents, with guy ropes and the like, when the rope generally forms a loop or has two running 40 parallel lengths. I do not wish, however, to be limited in the application of my improved rope lock, nor in its construction otherwise than required by the scope of the appended claims.

45 In carrying out my invention, I employ a bifurcated body member 5 comprising the two arms 6, 6 each of which is bent to form an eye 7.

50 8 is an eye or loop preferably centrally disposed with relation to the arms 6. As shown, the clamp body is bent from one piece of wire and the loop or eye 8 serves as a means for securing the one end 9 of the rope 10.

55 11 is a clamping lever formed as a closed oblong loop provided with eyes 12, 12 or

other means whereby said lever 11 is pivoted on the body member 5 in the said eyes 7, 7, in which the said clamping lever is adapted to oscillate or swing.

60 13 is a guiding means, as an eye, formed adjacent the one end of the loop 11 and through which eye the free end 14 of the rope passes out of the rope lock.

The clamping lever 11 is formed with 65 three substantial parallel parts comprising the two sides 15, 15 and the third part 16 which is a locking member formed in the shape of a flat S in two planes at right angles to each other as seen from Figs. 1 70 and 2.

75 It will be noted that the clamping lever 11 is formed out of one piece of wire, the ends 17, 17 of which are bent around the loop portions 15, 15.

Fig. 1 shows the use of the rope lock when there is a pull or strain upon the rope which strain or pull is indicated by the arrows 18, 18. It is then apparent that the free end 14 of the rope is locked or clamped at 19 in the 80 clamping lever 11 by the rope 10 and that the harder the pull is on the rope, the tighter it is clamped or pinched at 19 in the sharp bend around the locking member 16. Slight

85 adjustments to shorten the length of the rope may be made by relaxing the one end of the rope as shown at 20 in dotted lines when it is obvious that the free end 14 may be pulled through the eye 13 to shorten the loop of the rope. But for quick and 90

large adjustments to either shorten or lengthen the rope, the lever 11 is swung or tipped upon its pivots 12, 12 to a position about as shown in Fig. 3 where it will be 95

seen that the rope slides easily in either direction, being guided and straightened by the locking bar or member 16. The rope is quickly locked by moving the lever 11 into 100 its position within the clamp body 5, when a quick pull on the rope will again clamp the free end 14 and lock the rope.

I have found a rope lock constructed according to the drawing and the foregoing description to work perfectly and to provide 105 instantly operated means for quickly locking the rope in any adjusted position.

It will be observed that the clamp lever 11 lies nearly flat within the clamp body and that the operation and construction of the rope lock is very simple and efficient. 110

In case where it is desired to secure the rope lock to an object such as a ring in a

hitch post or when used with tents or sails, a hook 25, as shown in Fig. 4, may be provided or used without departing from the principle of the locking feature.

5. I claim:

1. A rope lock comprising a body member, a clamping member pivoted to said body member and a locking bar formed integral with said clamping member within the latter.

10 2. A rope lock comprising a body member, a clamping member pivoted to said body member, a locking bar formed integral with said clamping member within the latter and 15 a guiding means for the rope formed on said clamping member adjacent the one end thereof.

20 3. A rope lock comprising a body member, a clamping member formed as an oblong closed loop pivoted on said body member and movable within the latter, a locking member formed within said clamping member longitudinally thereof and a rope guid-

ing eye formed on said clamping member adjacent the one end thereof.

25 4. A rope lock comprising a bifurcated body member, an eye for securing the rope formed integral with said member, a clamping member forming a closed loop pivoted to the bifurcated portions of said body member and movable within the same, a locking bar formed integrally with said clamping member longitudinally thereof and a rope guiding eye on said clamping member adjacent the one end of the said locking bar.

30 5. A rope lock comprising a body member consisting of a centrally disposed eye and two arms, one on each side of said eye, a clamping member comprising a closed loop, pivoted in the free ends of the said two arms within the same and a locking and rope guiding bar within the said loop formed integrally therewith.

35 Signed at New York, N. Y., this 11th day of March, 1915.

JACOB C. N. WISTENDAHL.
